UNITED STATES PATENT OFFICE.

GRACE D. PULLMAN, OF NEW YORK, N. Y.

DOLL.

Application filed January 12, 1922. Serial No. 528,883.

The principal object of this invention is to provide a toy and display figure of any desirable size or shape representing a human form which may be quickly and readily 5 dressed with a piece of fabric of irregular formation without requiring any previous sewing or special cutting and by means of which a variety of artistic and effective costumes may be attached to the figure without 10 requiring any special skill or training.

For the accomplishment of these and such further objects as will hereinafter be apparent to those skilled in the art to which this appertains, the invention consists in 15 the construction, combination and arrangement of parts herein specifically described and illustrated in the accompanying drawings, wherein is shown a preferred embodiment of the invention, but it is to be understood 20 that changes, variations and modifications may be resorted to which fall within the scope of the claims hereunto appended.

In the drawings forming a portion of this specification:

25 Fig. 1 is a front view of a figure embodying my invention, part of the front section being broken away.

Fig. 2 is a front view of the figure shown in Fig. 1 dressed according to my invention, 30 a part of the dress and front section of the figure being broken away to clearly illustrate the manner in which the goods are secured.

Fig. 3 is a horizontal transverse section 35 on the line 3—3 of Fig. 2.

Fig. 4 is a side view of the figure shown in Fig. 1.

Fig. 5 is a perspective view of a modified 40 form of a figure embodying my invention and.

Fig. 6 is a section on the line 6—6 of Fig. 5.

As shown in Figs. 1 to 4, a doll designated generally by the numeral 10 is composed of two similar sections 11 and 12 which are held in spaced relationship one to the other by any desirable spacing means such as the blocks 13, so as to provide an inwardly extending narrow groove around 45 the perimeter of the figure. In effect, the groove so formed provides a recess for the reception of portions of the fabrics used for dressing the figure, which portions are tucked into said recess and in this manner 50 are completely concealed between the front and back of the figure and frictionally held

therein by engagement with each other and with the walls of said recess. The sections 11 and 12 and the blocks 13 may be secured together either by gluing the sections to the 60 block or by any other suitable or desirable means such as staples, eyelets, separable fasteners or the like.

The arms 14 of each of the sections are pivoted as at 15 and it will be understood 65 that the legs may be similarly pivoted if desired.

The outer extremities of the arms 14 of each of the sections are preferably brought into contact with each other and secured together for a short distance approximately from the finger tips to the wrists as shown at 14^a while the legs of each section may be joined together in a similar manner. I prefer, however, to provide an additional spacing block as at 16 adjacent the lower extremities of the legs and to flare the sections outwardly therefrom as at 17 to form a means for standing the doll on a horizontal 70 surface.

As shown in Figs. 5 and 6, the doll may be constructed as a three dimensional figure of any of the usual materials, such as plaster of Paris, bisque, papier mâché, etc., which may be moulded with a plurality of 85 grooves certain of which are interconnected and situated at suitable places around the perimeter of the figure and which may as shown in Fig. 5 comprise the longitudinal grooves 20 which extend down along each 90 side of the figure, the groove 21 which extends around the waist line, the groove 22 at the neck with the grooves 23 which extend off from the groove 22, the grooves 24 which extend along the arms and the 95 grooves 25 and 26 provided in the head. These grooves may obviously be produced in the moulding of the figure or may be cut out after the figure is removed from the mould.

The manner in which the doll is dressed or draped is clearly shown in Figs. 2 and 3 and is as follows, small pieces of fabric such as are commonly used for dress goods and which may be of irregular formation are 100 selected according to the costume desired to be improvised and the edges of the fabric are then pushed into the groove along one side of the figure, suitable means such as the flattened stick 27, a hair pin or any other 105 thin flat article being used to push the goods into the groove. After inserting the fabric 110

into the groove at one side of the figure, the other edge of the fabric is then inserted in a similar manner on the other side of the figure. It will be understood that the piece of fabric may be wide enough to extend all the way around the figure and be also long enough to improvise a one piece garment, or that separate pieces may be used for the front and back as well as for the skirt and 10 waist. The sleeves may be made of separate pieces which are usually placed on the figure before the rest of the costume is arranged in place or the whole costume may be devised from a single piece of material. 15 If desired suitable lace or other embroidery may be placed on the garment according to the fancy, as shown at 28 in Fig. 2. Should it be desired to place longitudinally extending strips of embroidery on the 20 figure as indicated at 29 in Fig. 2, the upper ends of the strips may be inserted in the groove adjacent the shoulders of the figure while the lower end of the embroidery may be secured by push pins as shown at 30 25 or a groove or slot 31 may be cut into the figure adjacent the waist line.

While I have used the term groove to apply to the space provided in which the material is to be thrust I wish it to be understood that the term is not to be considered as limited to a construction as shown in the drawings but that the term as used is intended to cover any groove or slot of any width or shape as would enable the pieces of 30 fabric to be thrust therein and retained in place by frictional contact of the inserted portions of the fabric with each other and with the sides or edges of the groove or slot.

40 Likewise it is to be understood that the term figure is not intended to be limited to a doll of any particular or limited dimensions as it will be obvious that my method of draping a figure would be equally applicable to displaying fabrics on life sized so called display figures or models such as are commonly used for window displays or show rooms, and would be of great value for displaying piece goods draped upon a figure to produce artistic costume effects without necessitating any cutting, sewing or other destruction of the goods from the piece or bolt of fabric.

Having thus described my invention what 45 I claim as new and desire to secure by Letters Patent of the United States, is:—

1. A toy and display figure having an unobstructed narrow groove forming a recess the bottom of which is located within the

confines of the outer surfaces of said figure, 60 said recess being of a width to permit irregularly shaped pieces of fabric being draped upon said figure to simulate a garment by insertions of portions of the fabric into said recess, said portions being held in 65 said recess only by frictional engagement with the walls thereof and with each other and being concealed in said recess.

2. A toy and display figure having a narrow groove forming a continuous recess extending into different portions of the figure and being of a width to permit irregularly shaped pieces of fabric being draped upon said figure to simulate a garment by the insertion of portions of the fabric into 75 said recess and the retention of said portions therein by frictional contact with each other and the walls of the recess.

3. A toy and display figure including 80 spaced front and back sections having substantially similar outlines representing the complete figure, and a spacing means to which said sections are rigidly secured in abutting relation thereto to form a groove arranged to permit irregularly shaped pieces 85 of fabric being draped upon said figure to simulate a garment by insertion of portions of said fabric into said groove, said portions being held in said groove by frictional engagement with the walls thereof. 90

4. A figure composed of substantially rigid front and back sections having substantially coextensive, similar outlines, means to secure said sections together in spaced relationship to form a narrow groove 95 between said sections extending inwardly from the periphery of said figure, and limbs pivotally secured to said figure, each of said pivotally secured limbs consisting of similar sections spaced apart at their point of connection to said figure and joined together at their extremities whereby a narrow groove is formed between the limb sections. 100

5. A toy and display figure having a narrow groove forming a recess therein and arranged to permit irregularly shaped pieces of fabric being draped upon said figure to simulate a garment by the insertion of portions of said fabric into said recess and the concealment of said portions therein, 105 said portions being held in said recess by frictional engagement with the walls thereof and with each other.

Signed at New York, in the county of New York and State of New York, this 115 day of January, A. D. 1922.

GRACE D. PULLMAN.
